(57) CLAIM

I claim an ornamental design for a lighting fixture, as shown and described.

DESCRIPTION

FIG. 1 is a perspective view of stage lighting of the present design;

FIG. 2 is a top view of the stage lighting of FIG. 1;

FIG. 3 is a bottom view of the stage lighting of FIG. 1;

FIG. 4 is a left side view of the stage lighting of FIG. 1;

FIG. 5 is a right side view of the stage lighting of FIG. 1;

FIG. 6 is a front view of the stage lighting of FIG. 1; and,

FIG. 7 is a rear view of the stage lighting of FIG. 1.

The shading in the figures show contour, not surface ornamentation, and form no part of the claimed design.

The dashed lines shown in the figures are for illustration only and form no part of the claimed design.
